UNITED STATES PATENT OFFICE.

WILLIAM THOMAS BUCKINGHAM ROBERTS, OF LEICESTER, ENGLAND, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR UTILIZING FASTENINGS.

1,312,578.

Specification of Letters Patent.

Patented Aug. 12, 1919.

Application filed March 21, 1916. Serial No. 85,605.

To all whom it may concern:

Be it known that I, WILLIAM T. B. ROBERTS, a subject of the King of England, residing at Leicester, Leicestershire, England, have invented certain Improvements in Machines for Utilizing Fastenings, of which the following description, in connection with the accompanying drawings, is a specification, like reference characters on the drawings indicating like parts in the several figures.

This invention relates to machines which utilize previously formed fastenings and is herein shown in its application to machines for use in the manufacture of boots and shoes. The invention is herein more particularly illustrated with reference to a multiple fastening inserting mechanism of a pulling-over machine of the type shown, for example, in United States Letters Patent No. 663,777 dated Dec. 11, 1900, although many features of the invention are applicable to shoe machines of other types than that of said Letters Patent, as well as to machines for operating upon work other than shoes, and may also be embodied in a fastening inserting machine adapted to deliver a single fastening to the driving mechanism during each cycle of operations of the machine.

In machines adapted to insert previously formed fastenings into stock the fastenings are commonly contained in bulk in a hopper from which they are conducted by one or more raceways, the fastenings being successively delivered from the raceway or raceways by a separator which has a single fastening separating movement for each cycle of operations of the machine. It often happens that the delivery of successive fastenings is irregular and this is frequently due to the fact that irregularities in the form of the fastenings cause the separating finger, which is usually connected yieldingly to its actuator, to be arrested during its fastening separating movement, thus suspending the delivery of any fastening to the fastening driving mechanism for that cycle of operations of the machine. In a multiple fastening delivering mechanism the possibilities of this occurrence are obviously multiplied, and the difficulty becomes of considerable importance in machines which drive from 5 to 11 fastenings at each cycle of operations as in a pulling-over ma-

chine. When the separator for any reason fails to deliver a fastening from any one of the raceways into position to be inserted in the operation of the pulling-over machine, the fact usually becomes known to the operator of the machine only after the work has been discharged from the machine and he perceives that the upper materials which have been pulled over upon the last have not been secured by a fastening in pulled-over position.

A general object of the present invention is to provide improvements in machines for utilizing previously formed fastenings whereby difficulties, such as those above described, arising from failure of a fastening delivering means to operate properly, shall be entirely avoided or reduced to a minimum.

The invention aims further to provide a multiple fastening delivering mechanism which is particularly adapted to obviate the difficulties heretofore experienced in the use of such mechanism.

In the illustrative embodiment of the invention the foregoing objects are attained by the provision of means adapted to become operative, in the event of the failure of the fastening delivering means to operate properly, to perform one or more functions, namely, to discharge or aid in discharging the fastening or fastenings, to give an audible or other warning upon the failure of a fastening to be properly delivered, or to prevent further operation of the machine and hence stop the operation of the fastening inserting mechanism. The invention in its broadest aspect contemplates the employment of means for performing any one of the functions above referred to and hence it is of course within the contemplation of the invention to provide means for performing, if desired, all of said functions.

In the illustrated embodiment of the invention the means employed for performing one or more of the specified functions is associated with the fastening separating device and preferably such device is in the form of a reciprocating separator which may be similar to that shown and described in prior United States Letters Patent No. 1,002,422. The separating device or slide is employed, in case it fails to separate a fastening from the other fastenings in the race-

way or fails to allow a fastening to pass to the inserting mechanism, to cause one or more of the above stated functions to be performed. In the embodiment of the invention herein illustrated, means is provided for effecting a continuous operation of the separator slide independently of its usual actuator which operation continues until a delivery of a fastening has been obtained and the slide has resumed its normal operation, and audible warning mechanism is also rendered operative and is maintained in operation until the normal operation of the fastening separating slide is assured.

In the construction shown there is combined with the separator slide and its actuator, which is yieldingly connected with the slide to allow relative movement in case the movement of the separator is arrested, an auxiliary actuator for the slide. In the illustrated embodiment of this feature of the invention this auxiliary actuator is automatically coupled to the separator slide when relative movement occurs between the slide and its main actuator. Conveniently the auxiliary actuator is reciprocated rapidly so that when it is acting as the actuator for the separator slide it will effect a rapid succession of forward movements of the slide in order to effect its object with as little loss of time as possible.

As illustrated, the auxiliary actuator member is preferably employed to cause the operation of the device or mechanism which gives the audible or other warning. In the construction shown the relative movement between the separator slide and its main actuator is additionally caused to render the machine inoperative so that the operation of the fastening driving mechanism will be suspended whenever the delivery of fastenings to it has been interrupted. According to one embodiment of this feature of the invention this rendering of the machine inoperative is accomplished by interrupting the connections between the main driving shaft and its controlling mechanism. The auxiliary actuating member may be and preferably is composed of two parts one of which is reciprocated continuously independently of the normal cycle of operations of the machine and the other part is so arranged as to be held stationary temporarily if any one of the return movements of the separator slide is arrested.

The invention will be better understood from the following description and the accompanying drawings, which illustrate a preferred embodiment of the above and other important features of the invention comprised in a multiple fastening delivering mechanism for a pulling-over machine of the type shown and described in the prior United States Letters Patent No. 663,777, above referred to, in which machine seven

tacks are delivered to the driving mechanism during each cycle of operations of the machine. Inasmuch as the illustrated machine is particularly adapted to handle small headed fastenings, for the purpose of description the term "tack" will be used instead of "fastening" in describing the various parts of the mechanism and the machine.

In the drawings,—

Figure 1 shows, in side elevation, a portion of a pulling-over machine in which the invention is embodied, a part of the mechanism being shown in vertical section;

Fig. 2 is a view, partly in section, of the fastening delivering mechanism looking in the direction of the arrow 2 in Fig. 1;

Fig. 3 is an enlarged vertical transverse section of the mechanism shown in Fig. 2;

Fig. 4 is a front elevation, partly in section, of the mechanism shown in Fig. 2, illustrating parts of the audible signal device; and

Fig. 5 is a detailed view, partly in section, of certain parts shown in Fig. 3.

The illustrated machine has a supporting frame comprising a base 2 which supports the head 4 of the machine upon which is mounted for rotation the usual tack hopper 5 in which the tacks are contained in bulk. The hopper 5 may be oscillated by a slide bar 6 which is provided with a rack for engaging a pinion carried by a shaft 7 which is fast to the hopper, as shown in United States Letters Patent No. 663,777, hereinbefore referred to. The tacks are lifted by paddles carried in the hopper and are deposited in raceways 8 which conduct the tacks to the separator where they are separated one by one from each raceway for delivery through tack tubes into coöperating tack blocks from which they are inserted into the shoe. As herein shown, a separator slide 10 is guided for suitable reciprocating movements in guideways on the machine frame and is operated by a main actuating member 12 which is provided with a recess containing a spiral spring 14 which is connected at its opposite ends to projections 13 extending from the ends of the separator slide 10. The main actuating member 12 is reciprocated through connections to the shaft 7 comprising a shaft 16 having at its upper end a beveled gear meshing with a coöperating gear on the forward end of the shaft 7 and having at its lower end pinion teeth 120 which mesh with the teeth of a rack provided on the under side of the main actuating member 12. The reciprocating movements are imparted to the separator slide 10 by its actuator 12 through the spring 14 and if the movement of the separator is arrested for any reason while the rack continues to receive movement the spring will yield so that damage to the machine parts will be avoided.

The separator slide 10 carries the fastening separating plate 15 located at the ends of the raceways 8 which convey the tacks from the hopper 5, the plate 15 being provided with the usual tack receiving throats 18 and tack separating points or fingers 20. The plate is arranged for reciprocation across the ends of the raceways 8 and acts to separate an individual tack from each of the raceways and to discharge or deliver the separate tacks into tack conducting tubes 22 by which they are guided into position to be inserted into the shoe. A complete reciprocation is normally imparted to the separator plate 15 at each cycle of operations of the machine as contemplated by said prior patents.

In the construction herein illustrated as embodying the present invention the separator slide 10 carries a depending bracket 24, Fig. 3, which extends partly under the rack bar or main actuating member 12, and supports two plungers 26, 28. Said plungers have recesses therein which, respectively, contain spiral springs 30 and 32. These spiral springs each have a bearing at one end upon the bottom wall of their respective recesses, and at the opposite end against a rigid portion of the bracket 24, and act to press the plungers 26 and 28 in opposite directions. The upper end of the plunger 26, which is pressed toward the rack bar 12, has a beveled surface 34 arranged to engage a like beveled or cam surface 36, formed on the under side of the rack bar 12, and conveniently formed as a step facing in the direction in which the slide 10 is moved in the operation of separating the tacks, as shown in Fig. 4. The lower end of the plunger 26 is T-shaped and a lateral projection 38 on one side of said plunger extends into a position to be pressed into engagement with a stop shoulder or abutment 40 formed in the bracket 24, while another projection 42 on the other side of the plunger is arranged to engage a corresponding shoulder 44 formed on the other plunger 28, which latter is pressed by its spring 32 in a direction to maintain the shoulder 44 and the projection 42 in engagement. The lower end of the plunger 28 is adapted to engage an angular notch 46, Fig. 5, in a bar 48 which is mounted for sliding movement in suitable ways, and moves in substantial parallelism with the direction of movement of the separator slide 10. This bar 48 serves as an auxiliary actuating member for the separator slide, and it is reciprocated constantly during the operation of the machine by mechanism independent of the mechanism that imparts the reciprocating movements to the separator slide. As herein shown, the bar 48 has at one end a fork 50 between the arms of which slides a block 52, and the block is provided with an aperture which forms a bearing for a crank pin 54 carried at the end portion of a shaft 56, supported in bearings carried by the head 4 of the machine. The shaft 56 is provided with a pulley wheel 58 which may receive power through a belt, 70 from any suitable source, but said power is applied independently of the application of power for the actuation of the other machine parts. The lower end of the plunger 28 is preferably beveled so as to correspond with 75 the shape of the notch 46, the direction of inclination of the bevel being substantially in the line of movement of the notched bar 48, and such bevel terminating in a sharp edge at that side of the plunger which faces 80 in the direction in which the separator slide is moved to separate the tacks.

During each complete cycle of operations of the machine, the main actuating member 12 is given a single reciprocation through 85 its connections with the shaft 7 and if the tacks are properly separated by the separator plate 15, at each reciprocation of the latter, the slide 10 will move with its actuating member 12; if, however, one of the 90 separating points 20 should encounter a tack which would arrest the operative movement of the slide the main actuating member 12 would move relatively to the slide, the spring 14 yielding to permit such relative movement. Movement of the rack member 12 relatively to the slide 10 will cause engagement between the beveled surface 36 on the rack member 12 and the coöperating bevel 34 at the end of the spring-pressed 95 plunger 26, thereby causing a depression of the plunger 26, which will move the projection 42 out of engagement with the shoulder 44 on the plunger 28, and thus permit the latter to be depressed by its spring 32, until its lower end enters the notch 46 in the auxiliary actuating member, or bar 48. Owing to the shape of the notch 46, and of the lower end of the plunger 28, the separator slide 10 will be connected with the auxiliary slide bar 48 in such manner that on the next return movement of the bar, which is being continuously reciprocated by the independent operating mechanism above described, the separator slide, and the separator plate 15 connected therewith, will be positively moved back, and, because of the frictional engagement between the end of the plunger 28 and the notch 46, which is caused by the pressure of spring 32, the separator slide will be yieldingly moved forward again on the next forward movement of the bar 48. This backward and forward movement which is imparted to the separator from the bar 48 auxiliates the initial 110 separating movement of the separator and acts to dislodge the obstructing tack, or to aid in the accomplishment of this result, the reciprocating movements of the separator slide continuing by reason of its connection 115 120 125 130

- with the continuously reciprocating auxiliary slide 48 until the tack or tacks which have been jammed are properly separated. In the event that the reciprocations which are imparted to the separator slide through connections to the bar 48 are not sufficient to immediately dislodge the obstructing tack, the plunger 26 will be forced out of the notch 46 on one of the forward movements of the bar, and said plunger will then reengage with the notch on the return movement so as to partake of at least a portion of the reciprocations of the bar, and such partial reciprocations will be imparted to the separator, successively, until the tack has become dislodged, whereupon the separator will resume its normal operation and continue to separate tacks from the raceways in its usual manner.
- 20 In lieu of the above-described connection between the separator slide 10 and the auxiliary actuating member 48, any other suitable connection may be employed which will have the desired capacity for yielding to permit a disconnection of the separator slide from the actuating bar for a portion of the stroke of said bar, in the event that a tack offers that amount of resistance to the proper movement of the separator that would tend to injure the separator or its actuating mechanism.
- 25 In order to provide a suitable warning in the event that the tacks should not be properly separated and delivered from any one of the raceways, the following construction may be provided.
- 30 Projecting from the lower end of the plunger 26 is a pin 60 having a rounded end which is adapted to engage, when the plunger 26 is depressed by the cam face 36, one end of a lever 62 which is preferably pivoted at 64 to the bar 48, as shown in Fig. 4. The opposite end of the lever 62 carries a hammer 66, and a bell, or other audible signal 68, is suitably mounted on the frame of the machine in position to be engaged by the hammer 66 when the lever 62 is vibrated. The end of the lever 62 which is engaged by the pin 60 is preferably corrugated, as shown in Fig. 4, and the parts are so arranged that while the plunger 26 is depressed and the bar 48 overruns the separator slide 10 on each ineffective attempt to move the latter to its full extent, the contact between the pin 60 and the corrugations on the lever 62 causes the lever 62 to be rapidly vibrated, which in turn effects a vibratory motion of the hammer against the bell and thus warns the operator that the normal operation of the tack separating mechanism has been interrupted. Cessation of the warning bell notifies the operator that the obstruction has been cleared and the separator is working freely again. Obviously the lever 62 may be so arranged as

to give a warning in other ways than those herein described, if desired.

The invention also contemplates the provision of means to prevent damage to the auxiliary separator slide actuating member 48, during the positive return movement of the separator slide 10, in the event that the latter encounters sufficient resistance to its movement at this time to endanger the parts of the device. For this purpose, the bar 48 is formed in two parts, one of which is connected with the fork 50 which receives motion from the crank pin 54, and the other of which parts contains the notch 46. These two parts are connected, as shown in Fig. 2, by a spring pressed abutment 69 which is mounted in a casing 70 projecting laterally from one of the parts and adapted to enter a recess in the other part, so that if that part of the bar 48 in which the notch 46 is formed should be arrested upon its return or backward movement the abutment 69 could ride out of its recess, and hence that part of the bar 48 which is provided with the notch 46, together with the elements which are driven from said bar, would not partake of the movement of the bar until such resistance was overcome.

A convenient means for temporarily rendering the machine inoperative in the event of failure of the separating mechanism to feed tacks properly, so that operation of the tack driving mechanism will be automatically suspended when the delivery of tacks to the driving mechanism is suspended, will now be described with reference to the tack supplying mechanism of a pulling-over machine of the type described in the specification of U. S. Letters Patent No. 663,777, above referred to.

The plunger 26 is provided with a lateral projection, (see Fig. 3), which may be conveniently, and as shown is, an extension of the hereinbefore described T-shaped projection 38 of the plunger. This projection is arranged over the forward end of a lever 72, Figs. 3 and 4, which is fulcrumed at 73 to a suitable rigid part of the frame of the machine, and the opposite end of this lever is connected by a Bowden wire 74 to one end of a pawl 75, which is pivoted on a stud 76 on the machine frame. This pawl is adapted to be moved, through the wire 74, in such manner that its opposite end 78 will be swung into position for engaging with certain parts of the starting and stopping mechanism of the pulling-over machine, the parts with which this pawl is associated and with which it co-operates to effect a stopping of the machine being illustrated in Fig. 1. These parts of the pulling-over machine are the same as those shown in Figs. 71, 72 and 73 of U. S. Letters Patent No. 663,777, and the reference characters herein employed are the same as those which are used in

designating like parts on the drawings of said prior patent. In the machine of said patent, a vertically sliding plate X^{42} is operated automatically at the end of the upper stretching part of the cycle of operation of the machine to depress a slide X^{48} , which in turn pushes down a spring-pressed rod 984 for controlling the engagement of the parts of the main clutch of the machine, 5 such clutch parts being permitted to separate for stopping the machine when said rod is moved downwardly. The rod X^{50} is connected to the treadle (not shown) which must be released and depressed again by the operator before the next part of the cycle of 10 operation of the machine, namely, the tack driving operation is initiated. Under normal conditions, the left hand end of a pivot latch X^{64} , carried on a slide X^{60} , is maintained in position to abut against the right 15 hand end of the slide X^{48} by a spring X^{70} and when the rod X^{50} is next raised by a depression of the treadle its beveled end X^{58} acts upon a coöperating bevel at the left 20 hand side of the slide X^{60} , and moves said slide toward the left, as viewed in Fig. 1, against the action of a spring X^{72} thus, through the pawl X^{64} , pushing the slide X^{48} against the spring X^{72} from under the 25 projection or sliding plate X^{42} . The slide X^{48} which is attached to the spring pressed rod 984, is then raised with said rod under the force of the spring which acts upon the latter, thereby permitting the clutch parts to 30 engage to start the machine. Referring now to the parts which are provided by the present invention for preventing operation of the machine when the tack separating mechanism fails to act, the elevation of the 35 right hand end of the pawl 75 will cause a depression of its opposite end, when the lever 72 has been actuated through depression of the plunger 26, in the manner above explained. Such movement of the pawl 75 40 will serve to move the left hand end of the pawl X^{64} down, so that it cannot engage with the slide X^{48} when the slide X^{60} is moved to the left upon depression of the starting treadle of the machine, and in consequence 45 the machine cannot be started on its tack-driving phase until the pawl 75 has been returned to normal position. The pawl 75 will remain in the abnormal position shown by dotted lines in Fig. 1 as long as 50 the movements of the tack separator are arrested, but as soon as the obstructing tack has been removed and the separator is thereby permitted to reciprocate, the plunger 26 will rise again under the influence of its 55 spring 30 and the pawl 75 will thus be permitted to swing back into normal position with its left hand end clear of the pawl X^{64} , so that the machine may resume its normal 60 operation upon the next depression of the treadle. The pawl 75 may be caused to re-

turn to its normal position by a spring, or any other suitable means. As herein shown, the right hand end of this pawl is made heavier than its left hand end, so that when pressure upon the end of the lever 72 is relieved the pawl will automatically return to its inoperative position. 70

It will be observed that the depression of the plunger 26 and the consequent movement of the lever 72 and the pawl 75 to render the machine inoperative are caused to occur independently of the operation of the auxiliary separator actuating bar 48, so that the machine will be prevented from carrying out its tack driving operation regardless of 75 whether or not the audible signal devices, and the devices to auxiliarily the movement of the slide 10 to clear jammed tacks from the raceways are employed. 80

It will also be apparent that the function 85 of the pawl 75 is to interrupt a connection between two members whose connection is a necessary pre-requisite to the starting of the machine, and obviously the pawl or an equivalent controlling member may be arranged to operate at any desired point in the control system of the machine to which it is applied. By way of example this pawl has been shown and described in position between two members which are to be thus 90 connected in the machine of the patent above referred to, but the invention is not limited to the use of such a device in the described, or in any other specific relation, as applicant believes himself to be the first to employ 95 any means for controlling the operation of the machine which is actuated through mechanism whose operation is effected when the tack supplying means fails to operate, regardless of the details of such mechanism, 100 or the particular machine in connection with which it is used. 105

Having described my invention, I claim as new and desire to secure by Letters Patent of the United States:— 110

1. In a machine of the class described, the combination with means for controlling the delivery of successive fastenings into position to be inserted, of a warning device, and means constructed and arranged to actuate 115 the warning device in consequence of an interruption in the normal operation of said first named means to deliver successive fastenings.

2. In a machine of the class described, the combination with fastening delivery means, of a signal, and means in operative relation to said fastening delivery means and the signal constructed and arranged to be rendered operative to actuate the signal when 120 any one of the normal operations of the fastening delivering means is suspended. 125

3. In a machine for inserting fastenings, the combination of means for controlling the delivery of successive fastenings into position 130

to be inserted, a signal device, and means constructed and arranged to actuate the signal device in consequence of failure of said controlling means to perform any one of its 5 normal fastening delivering operations.

4. In a machine for inserting fastenings, the combination of means for controlling the delivery of successive fastenings into position to be inserted, a signal device, and connections between the fastening controlling means and the signal device for automatically effecting an operation of said signal device upon failure of the fastening controlling means to deliver successive fastenings 10 into position to be inserted.

5. In a fastening inserting machine, the combination of a raceway, means for separating the endmost fastening in the raceway, a signal device, and connections between the separating means and the signal device for automatically rendering said signal device operative upon failure of the fastening separating means to separate the endmost fastening in the raceway.

25 6. In a fastening inserting machine, the combination of means for controlling the delivery of successive fastenings into position to be inserted, and means for giving a warning constructed and arranged to be 30 rendered operative automatically in consequence of abnormal inoperativeness of the fastening controlling means at any time during its fastening delivering operation.

7. The combination with a raceway, of a 35 fastening separator, an actuator arranged for movement with said separator but adapted to yield relatively to said separator when movement of the latter is arrested by a misplaced fastening, and means 40 arranged to be operated upon relative movement of said parts for giving an audible warning.

8. In a machine of the class described, the combination with a raceway, of a fastening 45 separator, an actuator connected yieldingly with said separator, a bell, a lever having on one arm a striker for said bell and having its other arm provided with corrugations, a plunger having a projection to engage 50 the corrugations, said plunger being operated to engage the corrugations upon relative movement of said separator and actuator, and means to move said plunger and lever relatively in the direction of the corrugations to actuate the striker.

55 9. In a machine of the class described, the combination with fastening delivery means, of means located in operative relation to the fastening delivery means constructed and 60 arranged to auxiliate the fastening delivering means to dislodge a fastening whose movement has been accidentally arrested.

10. In a machine of the class described, the combination with means for controlling 65 the delivery of fastenings, of an actuator

yieldingly connected with said means, and a second actuator arranged to be connected with said means upon failure of the delivery of a fastening engaged by said means.

11. In a machine of the class described, 70 the combination with means for controlling the delivery of fastenings, of an actuator yieldingly connected therewith, a reciprocating actuator normally disconnected from said means but arranged to be connected 75 therewith upon the failure of a fastening engaged by said means to be delivered and to impart its reciprocations to said means to dislodge the fastening.

12. In a fastening inserting machine, the 80 combination of means for controlling the supply of fastenings, and means for imparting additional operative movements to the controlling means upon its failure to control the supply of fastenings. 85

13. In a fastening inserting machine, the combination of a fastening separator having a yielding operative movement in one direction to separate a fastening from other fastenings, and means constructed and arranged to become operative to impart additional operative movements to the separator upon its failure to separate a fastening which it engages. 90

14. In a machine of the class described, a 95 raceway, means for separating the endmost fastening from the raceway and means for reciprocating said separating means upon failure of the separating means to separate a fastening in delivery position in the raceway. 100

15. In a fastening inserting machine, the combination of a raceway, a separator arranged for operative movement in a direction to separate the endmost fastening in the raceway, and means for automatically effecting a reciprocation of the separator when its operative separating movement is arrested. 105

16. In a fastening inserting machine, the 110 combination of a raceway, a separator arranged for movement in a direction to separate the endmost fastening in the raceway, and means for imparting additional reciprocations to the separator in fastening separating direction when its initial fastening separating movement is arrested. 115

17. In a fastening inserting machine, the combination of a raceway, a separator having an initial movement in direction to separate the endmost fastening in the raceway, and means for automatically imparting a plurality of reciprocations to the separator upon its failure to separate the fastening during its initial operative movement. 120

18. The combination with a raceway for fastenings, of a fastening separator, a main actuator yieldingly connected therewith, and an auxiliary actuator normally disconnected from said separator and adapted to 125

- be connected therewith upon failure of the endmost fastening to be separated and to then impart positive movements to the separator to dislodge said fastening.
- 5 19. The combination with a raceway, of a fastening separator, an actuator connected for movement with said separator but arranged for movement relative thereto when the normal movement of said separator is 10 arrested, an auxiliary actuator, and means rendered operative upon relative movement of the separator and first-named actuator to connect said separator and auxiliary actuator.
- 15 20. The combination with a raceway, of a fastening separator, an actuator connected for movement with said separator, a constantly reciprocated auxiliary actuator normally disconnected from the separator 20 and provided with a notch, and a plunger carried by said separator and adapted to enter said notch upon relative movement of the first-named actuator and the separator to connect the latter with the auxiliary actuator.
- 25 21. The combination with a raceway, of a fastening separator, a main actuator therefor, an auxiliary actuator having reciprocating movement, and means constructed and 30 arranged to connect said separator and auxiliary actuator upon relative movement of the main actuator and separator, said means being yieldable to permit disconnection between said parts in one direction of movement when the separator encounters undue 35 resistance to its movement in said direction, but arranged to move said separator positively in the opposite direction.
22. The combination with a raceway, of 40 a fastening separator, a main actuator yieldingly connected therewith and having a cam surface, a spring-pressed plunger, having a portion arranged for engagement with said surface upon relative movement 45 of said separator and said main actuator, an auxiliary actuator provided with a notch, a connecting member carried by the separator and operated upon movement of said plunger to enter said notch, and means for 50 positively reciprocating the auxiliary actuator.
23. The combination with a raceway, of 55 a fastening separator, a main actuator yieldingly connected therewith, an auxiliary actuator and means for positively reciprocating the same, and a locking device arranged to automatically connect said auxiliary actuator and separator upon relative movement of said main actuator and separator, said device being constructed and arranged to so connect said parts that reciprocating movements will be transmitted from the auxiliary actuator to the separator positively in one direction and yieldingly in the 60 other direction so that said connection will be temporarily broken in the event that the separator should encounter undue resistance to movement.
24. The combination with a raceway, of a track separator, a main actuator connected 70 for movements therewith when tacks are being properly separated, but arranged for movement relative to said separator when a tack becomes jammed, a two-part auxiliary actuator arranged to have one of its parts 75 connected with the separator when relative movement between the latter and said main actuator takes place, yielding means permitting disconnection of the parts of said auxiliary actuator when the separator encounters 80 undue resistance to tack-dislodging movements, and means connected with the other part of said auxiliary actuator for imparting reciprocating movement thereto.
25. The combination with a raceway, of 85 a tack separator, a main actuator therefor, a spring-pressed plunger carried by the separator and provided with a projection, a second spring-pressed plunger arranged for movement in a direction opposite to that 90 of the first-named plunger and having a shoulder to engage said projection, an auxiliary actuator for imparting tack dislodging movements to the tack separator, and means operated upon relative movement of the 95 main actuator and separator for moving the first-named plunger and thereby permitting movement of the second-named plunger for connecting said auxiliary actuator and separator.
26. In a machine of the class described, the combination with a raceway, of a fastening separator, an actuator having yielding connection with said separator, and means for imparting positive fastening dislodging 100 movements to the separator when its normal operative movements are arrested by an obstructing fastening.
27. In a machine of the class described, the combination with a raceway, of a fastening separator, an actuator having yielding connection with said separator, and means for imparting independent fastening-dislodging movements to the separator upon relative movement of said separator and 110 actuator.
28. In a machine of the class described, the combination with a raceway, of a fastening separator, a main actuator having yielding connection with said separator, a positively actuated auxiliary actuator operated independently of the main actuator, and means to lock the auxiliary actuator to the separator when the main actuator and separator are caused to move relatively.
29. In a machine of the class described, the combination with a raceway, of means for controlling the passage of fastenings in 120 said raceway, and means which is automatically rendered operative to auxilliate the fas-
- 130

tening controlling means to dislodge a misplaced fastening when movement of said controlling means is arrested by said fastening.

5 30. In a machine of the class described constructed to perform a normal cycle of operations and then stop, the combination with means for delivering fastenings, of devices constructed and arranged to be actuated in consequence of an interruption in 10 the normal operation of the fastening delivering means to prevent subsequent starting of the machine until such time as the fastening delivering means has been restored to 15 its normal operation.

31. In a machine for delivering fastenings and driving the same into work, the combination with a raceway, of a fastening separator, a main actuator yieldingly connected with the separator, controlling devices to start the machine including two members to be operatively connected, and means operated upon relative movement of 20 said main actuator and separator for interrupting the connection of said members and preventing the machine from operating.

32. A machine for feeding fastenings which are to be driven into work having, in combination, a raceway, a separator, a main actuating member having connection with said separator by means arranged to yield when the separator is arrested, controlling means for the machine including two members which are connected 35 when the machine is started, and means operated upon relative movement of said separator and actuating member to prevent said controlling members from being connected.

33. A machine for delivering fastenings 40 into position to be driven into work having, in combination, a raceway, a fastening separator therefor, a main actuator connected with the separator by means arranged to yield when movement of the separator is 45 arrested, a plunger actuated upon relative movement of said actuator and separator, a lever operated by movement of said plunger, a pawl having connection with said lever, and controlling means for the machine including two members which are operatively 50 connected when the machine is started, said pawl being arranged when moved to interrupt the connection between said members and prevent the starting of the machine.

55 34. In a machine for supplying fastenings and driving them into stock, the combination with means to control the supply of fastenings, of means to control the starting of the machine arranged to be rendered inoperative upon failure of the operation of 60 said first-named means.

35. In a machine of the class described, the combination with means for controlling the supply of fastenings to the point where 65 they are driven into work, of mechanism for

starting the machine prior to each driving operation, and means rendered operative by a misplaced fastening to prevent the operation of said mechanism.

36. In a machine of the class described, 70 the combination with means for controlling the supply of individual fastenings to the point where they are driven into work, of mechanism for starting the machine, and means for preventing the operation of said 75 mechanism upon failure of the delivery of a fastening to the driving point.

37. In a fastening inserting machine, the combination with means for controlling the supply of fastenings, of means for controlling the operation of the machine, and connections between said two named means constructed and arranged to cause the machine controlling means to prevent further operation of the machine when the fastening controlling means is rendered inoperative to 85 control the fastenings.

38. In a fastening inserting machine, the combination of means for controlling the supply of fastenings, means for effecting an 90 operation of the machine, and means for rendering the operating means inoperative upon failure of the operation of the fastening controlling means.

39. The combination with a raceway, of a 95 fastening separator, a main actuator connected with said separator for movement therewith but arranged for movement relative thereto when the separator is arrested, means operated upon relative movement of 100 said parts for giving an audible warning, and means for reciprocating the separator to dislodge the obstructing tack, said latter means being also operated upon relative movement of the separator and main actuator.

40. In a fastening inserting machine, the combination of means for controlling the supply of fastenings, a warning device, 110 mechanism for rendering the machine operative, and means for automatically actuating said warning device and simultaneously causing said mechanism to be rendered inoperative.

41. In a fastening inserting machine, the 115 combination of a raceway, a separator having operative movement in a direction to separate the endmost fastening in the raceway, mechanism for effecting an operation of the machine, and means constructed and 120 arranged to reciprocate the separator upon its failure to separate the fastening during its initial operative movement and for simultaneously rendering said mechanism inoperative.

42. In a fastening inserting machine, the combination of a raceway, a separator having operative movement in a direction to separate the endmost fastening in the raceway, mechanism for effecting an operation 130

of the machine, and means for imparting additional reciprocations to said separator upon its failure to separate a fastening during its initial separating movement, said 5 means rendering said mechanism inoperative until a fastening has been separated by the separator.

43. In a fastening inserting machine, the combination of a raceway, a separator having 10 operative movement in a direction to separate the endmost fastening in the raceway, mechanism for effecting an operation of the machine, means for imparting additional reciprocations to said separator upon 15 its failure to separate a fastening during its initial separating movement, and means for simultaneously rendering said mechanism inoperative until a fastening has been separated by said separator.

44. In a fastening inserting machine, the combination of a raceway, a fastening separator arranged to separate the endmost fastening in the raceway, an actuator for said separator, having a yielding connection therewith, an auxiliary actuator operating independently of the main actuator, mechanism for effecting an operation of the machine, means connecting the auxiliary actuator to the separator when the main actuator 25 and separator are caused to move relatively, and means to render said mechanism inoperative during the operation of said separator by the auxiliary actuator.

45. In a fastening inserting machine, the combination of a raceway, a fastening separator arranged to separate the endmost fastening in the raceway, an actuator for said separator having a yielding connection therewith, an auxiliary actuator operating 30 independently of the main actuator, mechanism for effecting an operation of the machine, means to connect the auxiliary actuator to the separator when the main actuator and separator are caused to move relatively, and means to render said mechanism inoperative until the normal operation of the separator by its main actuator has been resumed.

46. In a machine of the class described, the combination with fastening delivery means, and mechanism for imparting operative movement to said delivery means to cause 45 said means to deliver a fastening, of means constructed and arranged for operation in consequence of failure of said delivery means to complete an operative movement to give a signal to the operator.

47. In a machine of the class described, the combination with a raceway for fastenings, of a separator for effecting successive deliveries of fastenings from said raceway, means for operating said separator, and means constructed and arranged for operation in consequence of failure of said separa-

tor to complete any one of its operative 65 movements to give a signal to the operator.

48. In a machine of the class described, the combination with a raceway for fastenings, of a separator for effecting successive deliveries of fastenings from said raceway, 70 means for operating said separator, and means constructed and arranged for operation in consequence of interruption of a normal operative movement of said separator to signal the operator and to continue to signal the operator as long as said interruption continues.

49. In a machine of the class described, the combination with fastening delivery means and mechanism for imparting operative movement to said delivery means, of additional operating mechanism constructed and arranged to operate upon said delivery means to cause it to complete delivery of a fastening whose delivery movement has 85 been accidentally arrested.

50. In a machine of the class described, the combination with a raceway for fastenings and a separator, of means for imparting normal movement to said separator, and 90 additional means for imparting an abnormal movement to the separator in the event that its normal movement is accidentally arrested.

51. In a machine of the class described, the combination with a raceway for fastenings and a separator, of means for imparting normally a single reciprocatory movement to said separator, and means for reciprocating said separator a plurality of 100 times in the event that its normal movement is accidentally arrested.

52. In a machine of the class described, the combination with a raceway for fastenings, a separator and means for operating 105 said separator, of additional separator operating means, and mechanism arranged to be controlled by said separator for rendering said additional means effective to operate the separator upon a failure of the separator 110 to complete a normal movement.

53. In a machine of the class described, the combination with a raceway for fastenings, a separator and operating means for imparting a normal movement to said separator, of constantly driven supplemental operating means, and mechanism arranged to be controlled by the separator to effect a connection between the separator and said supplemental operating means upon a failure 115 of the separator to complete a normal movement.

54. In a machine of the class described, the combination with fastening delivery means, of mechanism having an automatically terminable cycle of movements for operating said delivery means, constantly driven supplemental operating mechanism,

and means for rendering said supplemental mechanism effective to operate the delivery means in the event of failure of said delivery means to complete an operative movement.

5 55. In a machine of the class described, the combination with a raceway for fastenings, of a separator for effecting successive deliveries of fastenings from said raceway, mechanism having an automatically terminating 10 able cycle of movements for operating said separator, constantly driven supplemental operating means for said separator, and means for rendering said supplemental means effective to operate the separator in 15 the event of failure of the separator to complete an operative movement.

56. In a machine of the class described, the combination with a raceway for fastenings, of a separator for effecting successive 20 deliveries of fastenings from said raceway, mechanism for imparting normally a single reciprocation to said separator in each cycle of operations of the machine, constantly driven supplemental operating mechanism, and means for rendering said supplemental mechanism effective to impart a plurality of reciprocations to said separator in 25 the event of failure of the separator to complete a normal movement.

30 57. In a machine of the class described constructed to perform a normal cycle of operations and then stop, the combination with starting means and fastening delivery means, of mechanism constructed and arranged to render said starting means ineffective to start the machine in consequence 35 of failure of said delivery means to perform its normal function.

58. In a machine of the class described

constructed to perform a normal cycle of 40 operations and then stop, the combination with starting means, a raceway for fastenings and means for delivering fastenings from said raceway, of mechanism constructed and arranged to render said starting 45 means ineffective to start the machine in the event of failure of said delivery means to effect the delivery of a fastening from said raceway.

59. In a machine of the class described 50 constructed to perform a normal cycle of operations and then stop, the combination with starting means, a raceway for fastenings and a separator for delivering fastenings from said raceway, of mechanism constructed and arranged to render said starting 55 means ineffective to start the machine in the event of failure of said separator to complete an operative movement.

60. In a machine of the class described 60 constructed to perform a normal cycle of operations and then stop, the combination with starting means, a raceway for fastenings and a separator for delivering fastenings from said raceway, of means for imparting a normal operative movement to said separator, supplemental operating means for the separator, mechanism for rendering said supplemental means effective to operate the separator in the event of failure of the separator to complete a normal movement, and mechanism for rendering said starting means ineffective to start the machine until said normal movement of the separator is completed. 70

75 In testimony whereof I have signed my name to this specification.

WILLIAM THOMAS BUCKINGHAM ROBERTS.
